CONTAINER CLOSURE

Herman H. Martin, Toledo, Ohio, assignor to
 H. H. Martin Products Corporation, Toledo,
 Ohio, a corporation of Ohio

Application March 20, 1939, Serial No. 262,816

6 Claims. (Cl. 215—74)

This invention relates to container closures, more particularly to closures of the fluid dispensing type, and the principal object of this invention is to provide new and improved closures of the character described.

In the drawing accompanying this specification and forming a part of this application, I have shown, for purposes of illustration, an embodiment which my invention may assume, and in the drawing:

Figure 1 is an elevational view illustrating an embodiment of the invention applied to a container, the container being fragmentarily shown,

Figure 2 is an enlarged vertical sectional view corresponding generally to the line 2—2 of Figure 1,

Figure 3 is a horizontal sectional view corresponding generally to the line 3—3 of Figure 2, and

Figure 4 is a perspective view illustrating parts of the embodiment in disassembled relation.

The embodiment herein shown comprises a closure 10, adapted to be connected to a container 11, such as a bottle or the like. The container 11, as here shown, is formed with a mouth or opening 12 defined by a neck portion 13, the latter having screw-threads 14 provided thereon.

The closure means, in the embodiment shown, comprises a body or cap means 15, formed of a substantially rigid material, such as a suitable molded plastic material, as for example, "plaskon" or "bakelite". The cap means 15 has a skirt portion 16 formed with interior screw-threads 17 adapted to interengage with the screw-threads 14 formed on the neck 13, so as to hold the body or cap means 15 assembled with the container 11. The cap means 15 has also a top wall 18, formed with a tubular portion or boss 19 extending from the upper surface thereof, the opening 20 in the tubular portion communicating with the interior of the skirt portion 16. The extremity of the tubular portion is formed with a valve seat 21.

Valve means 22 is carried by the cap means 15, and is so constructed and arranged as to move relative to the cap means. The parts comprising the valve means 22 are preferably formed of material similar to that forming the cap means 15. As shown, the valve means 22 comprises a valve member 23, having a valve surface adapted to cooperate with the valve seat 21, this valve surface, when seated on the valve seat 21, sealing the container 11. The valve means 22 also comprises guide means 24, having a plurality of ribs 25 so constructed and arranged that spaced

5 side marginal surfaces of each rib 25 have sliding engagement with the interior surface of the tubular portion 19 and the interior surface of the neck 13, for the purpose of guiding the valve means in its movement. In the embodiment shown, the guide means comprises four radial longitudinally extending ribs 25, arranged in substantially cross-formation in transverse section, as best seen in Figure 4. Each rib 25 has a lower 10 widened portion 26 of such width that the adjacent side margins of the ribs 25 slidably engage the interior surface of the bottle neck 13. Each rib 25 has also a narrow portion 27 of such width that the adjacent side margins of the ribs 25 slidably engage the interior surface of the tubular portion 19. Thus the guide means provides a plurality of spaced-apart bearing points, and the guide means operates to guide the valve means 22 in its movement, preferably holding the valve means 22 to longitudinal movement with respect to the bottle neck 13. Connected to the guide means 24 is a threaded stem 28, adapted to be received within a screw-threaded aperture 29 formed in the valve member 23.

20 To assemble the parts comprising the closure 10, it is merely necessary to insert the guide means 24 into the skirt portion 16 an amount until the threaded stem 28 extends up to the region defined by the valve seat 21, and then to 25 thread the valve member 23 onto the valve stem 28, such threading movement being limited by the upper ends, with reference to the drawing, of the ribs 25. When this is done, the valve member 23 and the guide means 24 will move 30 as a unit. It is preferable to seat a washer 30, of flexible material, such as cork, between the lip margin 31 of the neck 13, and the inner surface of the top wall 18, to provide an effective seal between the cap means 15 and the container 11.

35 Operation of the closure 10 is as follows: With the container 11 in substantially upright position, the weight of the valve means 22 is sufficient to hold the valve member 23 in seating relation on the valve seat 21, thus sealing the container 11. 40 When the container 11 is inverted, or tilted a sufficient amount, the valve means 22 is caused to move in a direction so that the valve member 23 is unseated from the valve seat 21, the widened portions 26 and narrow portions 27 of the ribs 25 sliding respectively along the interior surface of the neck 13 and the interior surface of the tubular portion 19, thus guiding the valve means 22 in its movement, and causing the valve means to move substantially in line with the axis of the container opening 12.

The closure provided by this invention forms an extremely compact unit, and when such closure is assembled with the container, the closure does not materially exceed the adjacent dimensions of the closure neck 13, nor does the valve means in any of its positions materially exceed the outline of the body or cap means 15. It will be appreciated that the closure is formed of material that is not readily attacked by fluids ordinarily carried by a container, and therefore fluid in the container cannot acquire an undesirable taste or odor from contact with the parts of the closure.

From the foregoing it will be apparent to those skilled in the art that I have accomplished at least the principal object of my invention, and it also will be apparent to those skilled in the art that the embodiment herein described may be variously changed and modified, without departing from the spirit of the invention, and that the invention is capable of uses and has advantages not herein specifically described; hence it will be appreciated that the herein disclosed embodiment is illustrative only, and that my invention is not limited thereto.

I claim:

1. In combination: a container, having an outlet opening; a body, having a dispensing opening, secured to said container and closing said outlet opening except for said dispensing opening, so that substance from said container is dispensable through said dispensing opening; and valve means carried by said body, comprising a valve member permitting flow through said dispensing opening when said valve means is shifted to one position, and interrupting flow through said dispensing opening when said valve means is shifted to another position, said valve means comprising also guide means having a first portion slidably engageable with a surface of said container, and a second portion slidably engageable with a surface of said body; said container surface, said body surface, and said guide means portions being relatively so constructed and arranged that said valve means is held to shifting along a predetermined path.

2. In combination: a container, having a neck surrounding its outlet opening; cap means, including a skirt portion fitting about the exterior surface of said neck, and a top portion generally overlying said outlet opening and being formed with a dispensing opening, said cap means closing the outlet opening of said container except for said dispensing opening; and valve means carried by said cap means in such manner that it is shiftable by gravity from one position to another, said valve means including a valve member disposed exteriorly of said cap means and so constructed and arranged as to control passage of substance through said dispensing opening, and including also guide means extending into said neck and having radially extending portions slidably engageable with the interior surface of said neck so as to hold said valve means to a shifting movement along a predetermined axis disposed in the general direction of the axis of said container neck; said valve means, when said container is in upright position, being gravity actuated to a position wherein said valve member closes said dispensing opening, and when said container is moved from upright position to a substantially inverted position, said valve member is gravity actuated to shift along said predetermined axis to a position

wherein said valve member uncovers said dispensing opening.

3. In combination: a container, having a neck surrounding its outlet opening; cap means, including a skirt portion fitting about the exterior surface of said neck, and a top portion generally overlying said outlet opening and being formed with a co-axial upwardly extending tubular boss communicating with the interior of said skirt portion and providing a dispensing opening, and said cap means closing the outlet opening of said container except for said dispensing opening; and gravity actuated valve means, carried by said cap means for shifting movement, comprising a valve member cooperable with the open end of said tubular boss for controlling flow through said dispensing opening, and guide means having a first portion slidably fitting the interior surface defining the opening through said tubular boss, and a second spaced portion slidably fitting the interior surface of said neck, said guide means being constructed and arranged to hold said valve means to a predetermined movement co-axial with respect to the axis of said container neck, and said second spaced portion being of such cross-sectional size that it abuts the inner surface of said top portion when said valve means has shifted a predetermined amount in the direction to uncover the open end of said tubular boss, and limits shifting movement of said valve means in this direction.

4. Closure means for a container having a neck surrounding the container opening, comprising: cap means, including a skirt adapted to fit about the exterior surface of the container neck, said cap means having a dispensing opening, and being so constructed as to close the container opening except for said dispensing opening; and valve means, carried by said cap means for movement relative thereto, including a valve member constructed and arranged to control flow through said dispensing opening, and guide means generally disposed within said cap means and having a portion spaced from the interior surface of said skirt portion an amount substantially corresponding to the cross-sectional thickness of the container neck, so that when said cap means is in position wherein its skirt portion fits about the exterior surface of the container neck, said guide means portion is in position to slidably engage the interior surface of the container neck and hold said valve means to a shifting along a predetermined path.

5. Closure means for a container having a neck surrounding the container opening, comprising: cap means, including a skirt adapted to fit about the exterior surface of the container neck, said cap means having a dispensing opening, and being so constructed as to close the container opening except for said dispensing opening; and valve means, carried by said cap means, movable to open or closed positions respectively providing for and preventing passage of substance through said dispensing opening, said valve means including a valve member constructed and arranged to control flow through said dispensing opening, and guide means connected to said valve member and extending through said dispensing opening and having a portion beyond said dispensing opening, said guide means having longitudinal passageway means so that substance from the container may pass therethrough and outwardly of said dispensing opening when said valve means is in

open position, and said guide means portion being of such lateral extent and so constructed and arranged that it is slidably engageable with the interior surface of the container neck when said cap means is in position on the container neck, so as to guide movement of said valve means.

6. Closure means for a container having a neck surrounding the container opening, comprising: cap means, including a skirt adapted to fit about the exterior surface of the container neck, said cap means having a dispensing opening, and being so constructed as to close the container opening except for said dispensing opening; and valve means, carried by said cap means for movement relative thereto, including a valve member constructed and arranged to control flow through said dispensing opening, and guide means connected to said valve member and com-

5 prising a plurality of legs extending radially from the longitudinal axis of said valve means, said legs being of such radial extent adjacent said valve member that the defining margins thereof are slidably engageable with the surface defining said dispensing opening, and said legs spaced from said valve member being of greater radial extent forming shoulders with the lesser radial extending part of the legs and being so constructed and arranged as to be slidably engageable with the interior surface of the container neck, said legs through such sliding engagement with said dispensing opening surface and the container neck surface guide movement 10 of said valve means, and said shoulders being engageable with a surface of said cap means to limit opening movement of said valve means.

HERMAN H. MARTIN.
